UNITED STATES PATENT OFFICE.

GEORGE E. SHEPARD, OF TROY, NEW YORK.

LETTER-FILE.

SPECIFICATION forming part of Letters Patent No. 286,233, dated October 9, 1883.

Application filed December 1, 1882. (No model.)

To all whom it may concern:

Be it known that I, GEORGE E. SHEPARD, a citizen of the United States, residing at the city of Troy, county of Rensselaer, and State 5 of New York, have invented a new and useful Improvement in Letter-Files, of which the following is a specification.

My invention relates to improvements in files for letters and bills, in which the letters and 10 bills are deposited between leaves of paper or other suitable material, provided with a suitable case or frame for holding the same; and it has for its objects to provide a duplex file formed by folding one continuous strip or webbing, so that the openings on one side of the web 15 between the leaves shall be separated by the thickness of the web from the openings formed on the other side, the openings on each side having letters or other symbols to distinguish 20 the contents, in connection or combination with a peculiarly-constructed case or frame for containing said duplex file and securing the contents. I attain these objects by the mechanism illustrated in the accompanying drawings, 25 in which—

Figure 1 is a perspective view of the file contained and held in the case. Fig. 2 is a perspective view of the file out of the case and with the folds or leaves partly opened to show 30 the manner of folding the webbing.

Similar letters refer to similar parts throughout the several views.

The frame shown in Fig. 1 is composed of the bed-plate A, with end pieces, B, attached thereto, connected on top by the cross-bar C, fastened to said end pieces. The end pieces are each provided with a perpendicular groove, D, in which rest and slide up and down the ends of the presser-bar E, which is continually 35 pressed downward by the ends of spring F, which is attached at its middle to cross-bar C. A web or strip of paper, cloth, or other suitable material or materials is folded together so as to form the leaves G G' G'' G''' &c., joined 40 at their opposite edges, as shown in Fig. 2, partly open or unfolded, the remaining leaves 45

(not marked) being closed or folded more closely together. The folds opening on one side, as G' and G''', may be used for letters, and the folds opening on the other side, as G'' and G''', may be 50 used for bills. Each opening on either side is provided with a suitable tag, as a b c, &c., used to open the fold, and which may be distinguished by a letter or other symbol to indicate the contents of that particular fold. The tags 55 range along down the edges of the folds, as is usual with index-letters, so that one shall not obscure the view of another. When the web is folded together and the folds closed, it may be placed in the frame, as shown in Fig. 1, and 60 the presser-bar E will serve to keep the folds compressed sufficiently close together to prevent the contents of the folds from slipping out. The folded web may be easily removed or inserted in the frame by raising with one 65 hand the presser-bar E and slipping the web out or in; but for general use the contents of either side of the file are accessible, and may be added to without removing it from the frame, which is of the greatest utility, as the 70 utility of a letter-file depends almost wholly upon its convenience and ready accessibility.

I am aware that a bill-file with a series of interleaves formed of a single sheet and folded in alternate directions, and a paper-file composed of a base, fixed end, sides, adjustable follower, with a hinged top section and a spring, 75 are not broadly new with me; but

What I claim as new, and desire to secure by Letters Patent, is—

The improved bill-file hereinbefore described, consisting of the case A, B, and C, with the presser E and spring F, and the duplex letter and bill holder G, with tags adapted to facilitate the opening of the folds, said parts being organized and arranged for access to the side pockets of the holder without disturbing the clamping means.

GEO. E. SHEPARD.
